UNITED STATES PATENT OFFICE.

HERMANUS THOMASSEN AND JACOBUS KROP, OF AMSTERDAM,
NETHERLANDS.

CORNISH BOILER.

SPECIFICATION forming part of Letters Patent No. 605,149, dated June 7, 1898.

Application filed October 9, 1897. Serial No. 654,632. (No model.)

To all whom it may concern:

Be it known that we, HERMANUS THOMASSEN and JACOBUS KROP, subjects of the Queen of the Netherlands, residing in Amsterdam, 5 Netherlands, have invented certain new and useful Improvements in Cornish Boilers, of which the following is a specification.

Our invention relates to an arrangement in Cornish steam-boilers by which the gases of 10 combustion as they leave the flame-tube are thoroughly mixed with each other and with the air required for combustion and again concentrated, perfect combustion and increased yield of heat to the walls of the flame-tube being thus effected.

The arrangement, which may be applied to any boiler of the type named, including those furnished with Galloway tubes, consists in placing a ring at the rear end of the flame-tube and at a short distance in front of it a disk, this latter leaving a small annular space between itself and the wall of the flame-tube. The area of this annular space between the disk and the flame-tube and also that of the 25 central aperture of the ring referred to are each substantially equal to the area of the free space over the fire-bridge. The effect of this arrangement is that the grate area may be reduced to the extent of one-half and a 30 saving of fuel to the amount of from twenty-five to fifty per cent. effected, while the production of steam remains the same.

The accompanying drawings illustrate the application of our invention to a Galloway boiler.

Figure 1 is a longitudinal section of the boilers. Fig. 2 is a back elevation of the same, and Fig. 3 is a front elevation of the disk designed to be inserted in the flame-tube.

In the rear end of the flame-tube *g* there is 40 inserted a ring *a*, the outer circumference of which is in contact with the inner wall of the flame-tube and the central opening *a'* of which is of substantially the same area as the free space *f* over the fire-bridge *d*. The ring *a* 45 may be made of metal or of fireproof material; but it is best to construct it of fire-clay. In front of the ring *a* in the interior of the flame-tube *g* is placed the disk *b*, which is 50 best made of cast-iron and is composed of two

parts united together, as shown in Fig. 3. The disk *b* may, however, be equally well constructed of fireproof material or of sheet iron or steel. It is arranged centrally in the flame-tube at a small distance from the ring *a* and 55 is secured in position by means of wedge-pieces *c*. A narrow annular space is left free between the disk *b* and the wall of the flame-tube, the area of this space being substantially equal to that of the free space *f* over 60 the fire-bridge and to that of the opening *a'* in the ring *a*.

The gases of combustion given off in the grate sweep along the wall of the flame-tube, become thoroughly intermixed with the air 65 of combustion at the point of their passage through the opening between the disk *b* and the flame-tube, and are then forced together by the ring *a*. At the point where the contraction occurs a further intimate mixture of 70 the gases of combustion and the air takes place, so that the gases burn while producing a great heat and pass into the lateral flues as pointed flames.

By making the area of the annular space 75 between the disk *b* and the flame-tube *g* and that of the central aperture of the ring *a* substantially equal to the area of the free space over the fire-bridge such mixture of air and gases is accomplished while securing a very 80 uniform speed for said air and gases as they pass through the boiler.

The arrangement described affords the advantage that it is susceptible of application without difficulty to Cornish boilers already 85 at work and that it has not the effect of making the flame-tube less accessible.

By constructing disks *b* in sections we facilitate their introduction and insertion into old boilers and provide for readily detaching the 90 same in case the interior of a shell is to be cleaned.

Having now particularly described and ascertained the nature of our said invention and in what manner the same is to be performed, 95 we declare that what we claim is—

1. In a Cornish steam-boiler, the combination with the flame-tube, of the fire-bridge, a sectional disk, wedge-pieces for arranging the same centrally in the flame-tube, a suitable 100

space being left between said disk and said tube, and a ring arranged behind the disk, substantially as set forth.

2. In a Cornish steam-boiler, the combination with the flame-tube, of the fire-bridge, a disk arranged centrally in the flame-tube, an annular space being left between said disk and said tube, and a ring arranged behind the disk the free space over the fire-bridge, 10 the annular space around said disk and the

central aperture of said ring being of substantially equal areas, all as set forth.

In testimony whereof we have signed our names to this specification in the presence of two subscribing witnesses.

HERMANUS THOMASSEN.
JACOBUS KROP.
